EDGAR C. CUMMINGS, OF WATERLOO, IOWA.

CONCRETE-MIXER.

1,096,154.

Specification of Letters Patent. Patented May 12, 1914.

Application filed July 28, 1913. Serial No. 781,540.

To all whom it may concern:

Be it known that I, EDGAR C. CUMMINGS, a citizen of the United States of America, and a resident of Waterloo, Blackhawk 5 county, Iowa, have invented certain new and useful Improvements in Concrete-Mixers, of which the following is a specification.

My invention relates to improvements in concrete mixers, and the objects of my improvement are, first, to provide rotary mixing blades for a concrete mixer, of a novel and efficient form; and second, to locate on one inner longitudinal wall of such a mixer a bracketed abutment or friction-plate secured therealong, impending over the blades, and close to their terminal points to aid the mixing operation in coöperation with said blades. These objects I have accomplished by the means which are herein- 10 after described and claimed, and which are illustrated in the accompanying drawings, in which:

Figure 1 is a perspective view of a portion of a concrete mixer of the open-trough type, and constructed according to my invention, with parts broken away to thereby disclose the interiorly-located rotary mixing-blades. Fig. 2 is an enlarged front elevation in detail of a pair of integrally-connected mixing blades, such as I use in intermediate positions within the mixing-casing, and Fig. 3 is a cross-section of one of said blades. Fig. 4 is a similar view of a pair of integrally-connected mixing blades, modified in form to rotate in close proximity to the end walls of the mixing-casing, and Fig. 5 is a cross section of one of said blades.

Similar numerals of reference denote corresponding parts throughout the several views. 40 The numeral 10 denotes the semi-cylindrical trough open at the top with its upper longitudinal edges bent obliquely upwardly at 13, and joined at their ends by like flanged out parts of the vertical end walls 45 11. The longitudinal upwardly directed sides of the trough have partially cut out parts 15, the parts 15 being bent outwardly and upwardly obliquely to provide relatively narrow and long horizontal longitudinal openings 14, extending nearly the whole length of the longitudinal parts of the trough near the bases of the upper

flanged-out parts 13. The lower part of the trough, being semi-cylindrical, a squared shaft 23 is seated axially in said trough, and 55 said shaft has sectional sleeves 24 mounted thereon, with the integrally connected mixing-blades 3 and 4 mounted fixedly on the shaft 23, between said sleeves, the sleeves serving as spacers for the blades. The ends 60 of the said shaft, are with their sleeves rotatably mounted in bearing openings in the end walls 11 of the casing to project outwardly therefrom, and desired means for producing rotation in said shaft may 65 be connected thereto, but not here shown.

I preferably employ in said mixer two forms of mixing blades, such as are shown in Figs. 2 and 3, and Figs. 4 and 5. The form of the blade shown in Fig. 2, has a 70 squared middle portion 1, having a square opening 2, adapting it to be fixedly seated on the shaft 23 between two spacing sleeves 24. Projecting in opposite directions from the part 1, and in the same plane therewith 75 are integral outwardly diminishing parts 3 and 4. The longitudinal edges of the parts 3 and 4 are flanged obliquely therefrom but the flanges 5 and 6 along said parts 3 and 4 on the same side are flanged 80 to extend in the same direction, while the flanges 7 and 8 on the other side of such parts are flanged in the opposite direction. Since the parts 3 and 4 are diminished outwardly gradually to points, the flanged out- 85 parts 5 and 7 on the part 3, and the parts 6 and 8 on the part 4 form, with said parts 3 and 4, blades diminished outwardly, but the parts with the flanges 5 and 7, and 6 and 8 are also truncated so as to make the 90 outer portions diminished to and in the same points with the parts 3 and 4, thus giving them the spadiform shape. This type of blade is employed within the mixer at intermediate locations along the said 95 shaft 23, but I use the other type of blades shown in Fig. 4, at the ends of said shaft immediately abutting upon the inner walls of the plates 11. The blade shown in Figs. 4 and 5, resembles that shown in Figs. 2 100 and 3, with this exception that the flat parts 3 and 4 of each blade have each but one oblique flange, shown at 9 and 6 respectively, such flanges being shown on op-

posite sides relative to each other, and projecting from the flat parts 3^x and 4 toward the interior of the casing and away from the abutting end wall 11, so that the flat parts 3^x and 4 lie closely adjacent to said end wall. It will be observed that both types of blades are so constructed as to serve solely as dashers or mixing-blades, and are not suitable for propelling material in the casing lengthwise therealong. The blades are preferably set upon said shaft 23 alternately at right angles to each other, as shown in said Fig. 1, which subserves the best results in mixing.

15 The lower left-hand part 17 of the semi-cylindrical bottom of the casing 10 is hinged at 18 to form a longitudinal outwardly swinging or drop-door, and which may be held in place and actuated by any suitable means not here shown. The casing part 10 has its lower part bent downwardly at 16 to form an oblique delivery-plate or chute, whose angle meets a longitudinal lower edge of said drop-door 17, and which is adapted 20 to receive the materials therefrom when said door is swung open. The lowermost part of the end-plates 11 is flanged outwardly, and supported upon transverse beams 12.

Referring to said Fig. 1, I have shown secured to the inner face of the upright part of one side of the trough 10, just above the drop-door 17, a bracket 21, whose upper edge coincides with the angle of the outwardly directed flange or shelf 15 on that side. Said bracket is bent inwardly to form an obliquely and downwardly directed shelf 20, which in turn, is bent downwardly to approach and be secured to said trough 10, with its latter part 19 formed on an arc of the cylinder, of which the bottom of the casing is a part so as to be supported concentrically about the shaft 23 and mixing blades 3—4, near the ends of said blades. As indicated by the arrow in said figure, the mixing blades rotate upwardly past the arc-shaped part 19, and said part 19 thus serves to fill in the space between the ends of said blades and the upper part of the trough wall, so as to prevent a dead space there, and also 50 to keep the materials together in the casing as the blades move through it, to be thereby more efficiently stirred up and mixed in the casing. It is, therefore, not necessary to have a similar projecting part 19 secured on the opposite wall of the casing, since the mixing-blades descend at that side.

60 The unmixed materials are deposited within the casing, and water may be introduced through the longitudinal openings 14, which latter lie above the general level of the mixing-blades. When the materials are sufficiently mixed, they may be discharged from the casing by means of lowering the drop-door 17.

Particular attention is called to the shapes 65 of the mixing-blades on account of their spadiform outwardly diminishing type, which being drawn to points, permits them to deliver material freely from their ends without sticking, and also enabling them to 70 handle the material more freely than if their ends were blunt, therefore, having a better dividing and mixing effect.

Having described my invention, what I claim as new, and desire to secure by Letters 75 Patent, is:

1. In a concrete-mixer, a rotary mixing-blade, formed with a middle portion lying in a plane at a right angle to the axis of rotation, said middle portion being gradually diminished outwardly to a point, and integral flanges on the longitudinal edges of said middle portion directed obliquely and oppositely outward from the plane thereof. 80

2. In a concrete-mixer, a rotary mixing-blade, formed with a middle portion lying in a plane at a right angle to the axis of rotation, said middle portion being gradually diminished outwardly to a point, and integral flanges on the longitudinal edges of 90 said middle portion directed obliquely and oppositely outward from the plane thereof, with the outer portions of said flanges gradually diminished outwardly to produce in conjunction with said middle portion a triangular end to the blade. 95

3. In a concrete-mixer, a rotary mixing-blade, having a middle portion provided with a central opening and with oppositely-projecting parts each gradually diminished 100 to a point, said middle portion lying in a plane set at a right angle to the axis of rotation, each edge of each of said diminished parts being bent obliquely thereto and oppositely therefrom, with the bent parts on 105 the same sides of the blade bent in the same direction.

4. In a concrete-mixer, a rotary mixing-blade having a middle portion provided with a central opening and with oppositely-projecting parts each gradually diminished to a point, said middle portion lying in a plane set at a right angle to the axis of rotation, each edge of each diminished part being flanged outwardly obliquely with the 110 flanges on each part projecting oppositely relatively to each other from the middle part, the flanges along one side of the middle part projecting oppositely from the flanges on the other side of the middle part, 115 and the outer parts of the flanges being diminished toward their ends to form with the pointed middle parts therebetween, triangular extremities for the blades. 120

5. In a concrete-mixer, a casing having a 125 semi-cylindrical lower part, a rotary shaft seated axially within said semi-cylindrical part, and having projecting mixing-blades

thereon, the casing extending upwardly from said semi-cylindrical part, and a bracketed friction-plate secured longitudinally along the inner wall of the upright part of
5 the casing along one side only, and arched over suitably to prolong the inner arc of the concavity of the semi-cylindrical part of the casing to overhang the upwardly-moving

ends only of the mixing-blades in close proximity to their extremities.

Signed at Waterloo, Iowa, this 9th day of July, 1913.
